US00D840218S

(12) **United States Design Patent** (10) **Patent No.:** **US D840,218 S**
(45) **Date of Patent:** **** Feb. 12, 2019**

(54) **PACKAGE WITH EARPHONES**

(71) Applicant: **Apple Inc.**, Cupertino, CA (US)

(72) Inventors: **Hamish Thain**, Brooklyn, NY (US);
Eric Treski, Manhattan Beach, CA
(US)

(73) Assignee: **Apple Inc.**, Cupertino, CA (US)

(**) Term: **15 Years**

(21) Appl. No.: **29/621,348**

(22) Filed: **Oct. 6, 2017**

Related U.S. Application Data

(63) Continuation of application No. 29/529,588, filed on Jun. 9, 2015, now Pat. No. Des. 799,316.

(51) **LOC (11) Cl.** **09-03**

(52) **U.S. Cl.**

USPC **D9/415; D9/432**

(58) **Field of Classification Search**

(57) **CLAIM**

The ornamental design for a package with earphones, as shown and described.

DESCRIPTION

FIG. 1 is a top front perspective view of a package with earphones showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the figures show portions of the package with earphones that form no part of the claimed design.

1 Claim, 6 Drawing Sheets
